UNITED STATES PATENT OFFICE

2,612,396

LOCK FOR UPWARD ACTING DOORS

Anthony Venditti, Detroit, Mich., assignor to
Crawford Door Company, Detroit, Mich., a corporation of Michigan

Original application November 22, 1944, Serial No. 564,596, now Patent No. 2,552,752, dated May 15, 1951. Divided and this application October 12, 1946, Serial No. 703,042

2 Claims. (Cl. 292—47)

1.

This invention relates to devices for locking closures, and specifically deals with a flipper assembly for pulling a tilting door into fully closed position and for locking the door in a doorway.

This application is a division of my copending application entitled: "Upward Acting Door Construction," Serial No. 564,596, filed November 22, 1944, now Patent No. 2,552,752, issued May 15, 1951.

While the locking devices of this invention will hereinafter be specifically described in connection with upward acting closures for buildings, garages, and the like, it should be understood that these locking devices are generally useful for pulling members or parts into closed position and for locking the members or parts in the closed position.

Upward acting doors generally swing on links or arms from closed vertical position to open overhead horizontal position, while the upper ends of the doors are supported on overhead horizontal tracks. This invention provides locking devices which will pull the substantially closed doors into fully closed position and lock them in the fully closed position.

It is, then, an object of this invention to provide locks for tilting closures which will pull the closures into fully closed position and hold them in locked condition in such position.

A further object of this invention is to provide flipper devices for holding upward acting or tilting door constructions in fully closed position even when the door constructions do not gravitate to such position.

Another object of the invention is to provide locks for upward acting doors having spring-retracted flippers which are forced into locking position by readily operated slide bars.

Another object of the invention is to provide locks for upward acting doors which are spring-impelled to open position and are positively impelled against spring action into locked position.

Other and further objects of the invention will be apparent from the following detailed description of the annexed sheets of drawings which, by way of a preferred example only, illustrate one embodiment of the invention.

On the drawings:

Figure 1 is an elevational view of a doorway, viewed from the inside thereof, and having a door locked in closed position by locking devices according to this invention.

Figure 2 is a broken vertical cross-sectional view, with parts in elevation, taken along the line II—II of Figure 1 but illustrating the door in partially opened position in the doorway.

2.

Figure 3 is an enlarged fragmentary horizontal cross-sectional view, with parts omitted, taken along the line III—III of Figure 1.

Figure 4 is a front elevational view of the assembly of Figure 3.

As shown on the drawings:

In Figures 1 and 2, the reference numeral 10 designates a door for opening and closing a doorway 11 defined by a top lintel 12, side door jambs 13, 13, and a floor F.

Overhead tracks 14, 14 project inwardly from the doorway 11 at levels adjacent the lintel 12. These tracks 14 have front end flanges 14a secured to the inner faces of the side door jambs 13 by means of square-headed screws 15. The tracks 14 also have flanges 14b at their rear ends as best shown in Figure 2, which are secured by means of bolts 16 to brackets 17 depending from an overhead beam 18 carried by the building containing the doorway 11.

The tracks 14 have curved bottom flanges 14c and flat top flanges 14d overlying the curved flanges. The flanges support and retain rollers 19 having axles 20 retained in the curled top ends 21a of weatherstrips 21. The weatherstrips 21 have outer portions for overlying the inner faces of the door jambs 13 and inner portions overlying the inner face of the door 10.

Each weatherstrip 21 is welded to the inner flange 22a of a channel strip 22 embracing the side edges of the door. The channel strip 22 extends from the top to the bottom of the door and the weatherstrip 21 is welded to the upper portion only of the strip.

The lower portion of each channel strip 22 has a bracket 23 welded to the inner flange 22a thereof. The brackets 23 are pivotally connected to the lower ends of link arms 24 by means of rivet-like pivot pins 25. The upper ends of the link arms 24 are pivoted to brackets 26 by means of rivet-like pivot pins 27. The brackets 26 are riveted or welded onto elongated weatherstrips 28 which are secured to the inner faces of the door jambs 13 and extend downwardly from the lower ends of the weatherstrips 21 to the bottom of the door. Wood screws 29 secure the weatherstrips 28 to the door jambs.

The upper ends of the weatherstrips 28 have brackets 30 riveted or welded thereon. These brackets 30 project inwardly from the inner faces of the door jambs 13 and also project laterally into the doorway 11. Rocker members 31 are pivoted to the laterally inward end faces of the brackets 30 by means of pivot pins 32. Spring retainer members 33 are pivotally connected to the rockers 31 by means of pivot pins

34. Coil springs 35 have the upper end coils thereof wrapped around the retainers 33. The lower end coils of the springs 35 receive retainers 36 which are hooked onto integral hook portions 24a of the link arms 24.

The door is thus secured at its side edges in the channel strips 22 and the upper end of the door is suspended from the tracks 14 through the rollers 19, axles 20, and weatherstrips 21 welded on the channel strips 22. The lower end of the door is pivotally connected through the link arm 24 with weatherstrips 28 secured to the door jambs. The door is thereby mounted in the doorway for swinging movement from the closed vertical position shown in Figure 1 through the intermediate open position shown in Figure 2, to a fully opened overhead position lying horizontally parallel with the tracks 14. The link arms 24 will swing about their pivots 27 from downwardly extending position, shown in Figure 1, to upwardly extending position for holding the bottom end of the door adjacent the lintel 12. The double pivots 32 and 34 for the upper end of the spring are arranged so that the spring will have a straight upward pull on the door in closed vertical position to prevent slamming of the door into closed position and an inward pull on the door in overhead position to hold the door open.

In order to lock the door in closed position, flipper devices best shown in Figures 1, 3 and 4 are provided on the inner face of the door 10 adjacent the side edges thereof at levels beneath the pivotal axes 27 for the door. As shown in Figures 3 and 4, a plate 37 is welded on the inner flange 22a of the channel strip and projects therefrom over the door to be secured to the door 10 by means of screws or the like. The plate has an offset portion 37a overlying and welded to the flange 22a of the channel strip 22 and, to permit full seating of the flange 22a on the weatherstrip 28, the weatherstrip 28 has an offset localized portion 28a thereof receiving the forwardly projecting end 37a of the plate. The arrangement is such that the weatherstrip 28 will contact the flange 22a of the channel strip along its entire length except at the localized portion 28a thereof. This portion 28a thereof will contact the plate portion 37a.

Raised portions 37b are formed on the plate in spaced opposed aligned relationship to define pivot supports for a flipper member 38. The flipper member 38 has an offset front end portion 38a for engaging the weatherstrip 28. Ears 38b are provided on the sides of the flipper in spaced relation from the end 38a thereof and a coil spring 39 is anchored at one end to each ear 38b and at the other end to a tang 37c turned up from the edge of the plate 37. The springs 39 pull the flipper 38 to the dotted line position shown in Figure 3, in which position the flipper will clear the inner edge of the weatherstrip 28.

A slide bar 40 is slidably mounted through a slot in an upstanding flange 37d of the plate, and through an aligned slot in an upstanding ear 37e of the plate.

The bar 40 has an upturned end portion 40a for acting as a presser foot to slide over the flipper 38 and depress it into locked position as shown in Figure 3. As indicated by the dotted lines in Figure 3, the bar 40 rocks relative to the plate 37 as it is moved from flipper-releasing position shown in dotted lines to flipper-locking position shown in solid lines. This rocking action provides a wedge for securing the flipper in locked position.

The inner end of the bar 40 is offset as at 40b

and the offset portion is apertured to receive an actuating rod 41. A cotter pin 42 retains the rod in the aperture of the offset portion 40b. The rod 41 extends along the inner face of the door as best shown in Figure 1, to an actuating bar 42 of a lock device 43 secured on the inner face of the door. The device 43 has a handle 43a which, when turned, draws the bar 42 inwardly to pull the rod 41 and effect a sliding of the bar 40 to a position so that the spring 39 will release the flipper 38 from locked position. A similar bar 42a actuates a similar rod 41a to the lock bar 40 of the other locking device.

The flippers 38, upon being forced to locking position by the bars 40, serve to pull the door into a fully closed position in the event that the door has not been fully closed, since the offset portions 38a of the flippers will engage the weatherstrips 28 and draw the channel flanges 22a into tight engagement with the weatherstrips.

Each weatherstrip 28, as also shown in Figure 1, has an inwardly offset localized portion 28b beneath the portion 28a thereof to form a pocket for receiving the bracket 23 when the door is in closed position, so that the flange 22a of the channel strips will not be held in spaced relation from the weatherstrips by the thickness of this bracket.

As illustrated in Figure 2, the link arms 24 are bent to provide depressed portions 24b in alignment with the flipper plates 37 and actuating bars 40 when the door is in closed position, so that sufficient clearance will be obtained for the locking device.

From the above descriptions it should be understood that this invention now provides locking devices composed of flippers which are spring-impeled to open position and are actuated to closed locking position against spring action by means of presser feet or lock bars. The flippers are adapted to engage door jambs of a doorway for pulling a door into fully closed position. When the lock bars or presser feet actuate the flippers against the spring action, the flippers are locked against further movement and the door is locked in the doorway.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. In an upward acting door construction of the type including a door tiltably mounted in a doorway, an improved locking means comprising, weatherstrips adapted to overlie the inner face of the door at the side edges of the doorway, offset pockets formed on said weatherstrips, plates adapted to be mounted on the inner face of the door and having offset mating portions arranged to project into said pockets when the door is closed in full engagement with said weatherstrips, flippers pivotally mounted on said plates and each having an arm portion adapted to overlie the weatherstrips in thrusting engagement therewith, springs stretched between said plates and said flippers for pivoting the flipper arm portions to extend inwardly from the side edges of the door, lock bars slidably mounted on said plates and having offset free ends constituting presser foot portions arranged to slide over and depress said flippers against the bias of said springs, and means for propelling said lock bars toward said flippers to swing the flippers about their pivots against the

spring pressure into thrusting engagement with the weatherstrips, said flippers having bent-over end portions cooperable with said weatherstrips for pulling the door into closed position and for clamping the door in said closed position.

2. A closure structure for a tilttable garage door apparatus of the type including a doorway frame closed by a tilttable door abutting a retainer around the doorway, comprising, clamping means to clamp the door in locked closed position against the retainer including a plate to be attached to the door adjacent one edge thereof, an interlocking mating member on said plate to engage the retainer at a predetermined aligned position, an arm member pivotally mounted on said plate and extending beyond said one edge of said door to engage a portion of the retainer overlying the doorway, biasing means normally urging said arm member inwardly of said one edge of said door into clearance relationship relative to the portion of said retainer overlying the door, guide means on said plate, and a slidably actuating bar carried by said guide means, said actuating bar having a

pressure foot formed at one end thereof to engage said arm member in wedge relation, whereupon selective reciprocation of said bar will wedge said arm to clamp said door against said retainer in locked closed position.
